UNITED STATES PATENT OFFICE.

FRANZ THELITZ, OF HENNEF-ON-THE-SIEG, GERMANY.

CENTRIFUGAL SEPARATOR FOR PURIFYING OILS.

1,002,471.

Specification of Letters Patent.

Patented Sept. 5, 1911.

Application filed February 21, 1907. Serial No. 358,651.

To all whom it may concern:

Be it known that I, FRANZ THELITZ, merchant, a subject of the King of Prussia, German Emperor, and residing at Hennef-on-the-Sieg, in the Kingdom of Prussia, German Empire, have invented new and useful Improvements in Centrifugal Separators for Purifying Oils, of which the following is a specification.

- 10 The present invention relates to centrifugal separators and an important object is to provide an improved separator for purifying used lubricating oil from its foreign constituents, such as water, dust and the like.
- 15 In order that the invention may be clearly understood, reference will be made to the accompanying drawings in which several embodiments are represented by way of example, and in which:
- 20 Figure 1 is a vertical section through one constructional form, Fig. 2 being a cross-section through the same in the plane A—B in Fig. 1; Fig. 3 is a vertical section through a second constructional form, in the plane 25 C—D in Fig. 2.

Referring to the drawing, the centrifugal separator represented in Fig. 1 has a revolvable drum *b*, into which a feed pipe *a* projects from above through an orifice in the top 30 of the drum; the lubricating oil which has been used can be uninterruptedly run into the drum through this feed pipe *a*. The latter is open at its lower end and opens above a plate *c* which is integral with or rigidly attached to the drum *b*. The plate is rather larger than the orifice in the drum, so that its edge projects beyond the limits of the orifice which are indicated by dotted lines. For rotating the drum, the shaft *z* of the 40 same is provided with a pulley *x* which can be driven by a rope *y*. Around the plate *c* there is arranged a conical insertion *d*, the upper end of which projects above the plate and the top opening of which has a smaller 45 diameter than the plate *c*. At the lower edge of this conical insertion there are provided slots or holes *p* through which the space in the drum under the insertion is connected with the space in the drum above the insertion. 50 Near the upper end of the insertion *d* there is built into the interior of the drum a partition *e* which has a central opening and is perforated like a sieve. Radial plates *u* carrying the conical insertion *d* and the partition *e* are arranged in the drum *b*. Above 55 this partition is situated the mouth of a pipe

f which admits of the purified oil being continuously conducted away from the drum. The mouth of this pipe *f* has a vertical projecting edge *g* and the rim of the mouth is curved concentrically with the periphery of the drum. The partition *e* may also be perforated like a sieve near its interior edge only. Also it may be provided with a filter *e'*, and moreover it may be conical in shape. 60 65

The action of the constructional form represented in Fig. 1 is as follows:—The pipe *a* conducts the used lubricating oil to the plate *c* which rotates with the drum *b* when the latter is rotated and throws the oil flowing 70 onto it to the outside. The used lubricating oil contains usually foreign constituents as dust, mud, coagulated oil-portions or like firm substances and water. The oil which runs off the plate *c* flows downward along 75 the insertion *d* and arrives at the openings *p* in the lower edge of the same. In consequence of the centrifugal action the foreign constituents of the oil are sent to the outside, and pass along the cone *d* into the lower part 80 of the drum. The water and constituents less weighty than the oil go with the oil through the openings *p* of the conical insertion *d*, while the firm and more weighty 85 foreign constituents collect at the wall of the drum under the cone *d* and must be removed from time to time. The oil, which is largely liberated from impurities, flows into the space bounded by the drum *b*, insertion *d* and partition *e*, penetrates through the sieve-like holes in the partition *e*, and in consequence of the centrifugal action fills the drum from the inner wall of the same up to the limits indicated by the dotted lines. 90 The function of the conical insertion *d* is to cause the oil and its impurities to be passed over a long way and to separate in the lower portion of the drum the more weighty impurities from the oil and to prevent them to be re-mixed with the purified oil collecting 95 above the cone *d*. When the drum rotates, the rim *g* at the mouth of the pipe *f* skims off the inner layer of the purified oil, the position of which layer is indicated by the dotted line *v* in Fig. 2. The oil which is 100 thus taken up enters the pipe *f* and flows through the same. 105

The constructional form represented in Fig. 3, in which the feed pipe is not represented, is not only suitable for continuously 110 conducting away purified oil, but also for continuously carrying off the water which

is separated from the oil. The skimming pipe *f*, which projects through an orifice in the cover *h* of the drum *b*, serves for conducting away the purified oil. The top 5 of the hub of the drum here forms a plate *c* corresponding in size to that shown in Fig. 1. For drawing off the water which, together with the other impurities, collects at the wall of the drum, there is arranged 10 under the cover *h* of the drum a radially directed pipe *i* which is open at both ends. The one end of the pipe *i* extends nearly to the wall of the drum and dips into the water which is at the periphery of the drum. 15 Near the other end of the pipe *i* there is in its wall a hole *o* which is in communication with the hole *l* in the cover *h* of the drum. Into the pipe *i* is screwed a hollow screw *k*, the position of which may be varied by 20 turning it. The position of the water in the drum can be regulated by means of this screw. The farther the screw is removed from the wall of the drum, the more liquid can collect in the drum and the deeper will 25 be the layer of water, since the mouth of the screw forms simultaneously the outlet for the water and the depth of the layer of liquid is dependent on the distance of this outlet from the wall of the drum. The 30 nearer the screw is approached to the wall of the drum, the less liquid can collect in the drum and the shallower will be the layer of water. The partition *e* is entirely made like a sieve, and is provided with a 35 filtering layer *e*¹. In this constructional form, as in those shown in Figs. 1 and 4, the drum is rotated by means of a rope *y* which drives a pulley *x* on the shaft *z* of the drum.

40 What I claim as my invention and desire to secure by Letters Patent is:

1. In a centrifugal separator, for purifying used lubricating oil and the like, the combination of a revoluble drum having a 45 central orifice in the top of the same, and a plate-like surface centrally in the drum of larger diameter than said orifice, a conical insertion in the drum extending above said

plate-like surface and having apertures at its lower circumference, a horizontal perforated partition fixed in the drum in immediate proximity to the top of said conical partition, and a skimming pipe having a mouth concentric with the wall of said drum and arranged between said partition 55 and the top of the drum.

2. In a centrifugal separator, for purifying used lubricating oil and the like, the combination of a revoluble drum having a central orifice and a hole located laterally 60 thereto in the top of the same, and a plate-like surface centrally in the drum of larger diameter than said orifice, a conical insertion in the drum extending above said plate-like surface and having apertures at its 65 lower circumference, a horizontal perforated partition fixed in the drum in immediate proximity to the top of said conical partition and a radially directed pipe mounted below the top of the drum and 70 terminating at one end below said hole and at the other end near the periphery of the drum.

3. In a centrifugal separator, for purifying used lubricating oil and the like, the 75 combination of a revoluble drum having a central orifice in the top of the same, and a plate-like surface centrally in the drum of larger diameter than said orifice, a conical insertion in the drum extending above said 80 plate-like surface and having apertures at its lower circumference, a horizontal perforated partition fixed in the drum in immediate proximity to the top of said conical partition, and a radially directed pipe 85 mounted below the top of the drum and terminating at one end below said hole and at the other end near the periphery of the drum, said radially directed pipe being provided with a hollow adjustable screw. 90

In witness whereof I have hereunto set my hand in presence of two witnesses.

FRANZ THELITZ.
